UNITED STATES PATENT OFFICE.

WALTER H. BALDWIN, OF CHICAGO, ILLINOIS.

HOISTING APPARATUS.

No. 820,844.

Specification of Letters Patent.

Patented May 15, 1906.

Application filed March 17, 1905. Serial No. 250,534.

To all whom it may concern:

Be it known that I, WALTER H. BALDWIN, a citizen of the United States, residing at Chicago, in the county of Cook and State of Illinois, have invented a new and useful Improvement in Hoisting Apparatus, of which the following is a specification.

My invention relates particularly to safety appliances for hoisting mechanism of the character commonly employed in connection with inclined railways; and my primary object is to provide automatic mechanism for preventing the drum of the hoisting mechanism from paying out the cable and allowing the car to run uncontrolled down the incline in the event of the failure of the engine or any working part of the hoisting mechanism.

My invention is illustrated in the accompanying drawings, in which—

Figure 1 represents a plan view, partly in section, of hoisting mechanism equipped with my safety appliance; Fig. 2, a partial section, on an enlarged scale, taken as indicated at line 2 of Fig. 1; and Fig. 3, a broken section taken as indicated at line 3 of Fig. 2.

In the construction shown, A represents a frame having journaled therein three parallel shafts B, C, and D. Power may be communicated to the shaft B from an engine (not shown) through the medium of a sprocket-wheel b. A pinion b', fixed on the shaft B, meshes with a gear c, journaled on the shaft C, and a pinion c', fixed on the shaft C, meshes with a gear d, fixed on the shaft D. Journaled on the shaft D is a drum E, to which is applied a hoisting-cable e. Secured to the drum at one end thereof is a friction-wheel e', to which is applied a brake-band e'', controlled by a rock-shaft e'', arm e', and hand-wheel-equipped screw e'' in the usual manner. The usual manually-operated clutch mechanism F serves to connect the drum to the shaft D at will.

Shiftably keyed on the shaft C is a brake-wheel G, to which is applied a brake-band g. As shown, the key g' of the wheel G works in a transverse slot g' in the shaft C and serves as a medium for shifting the wheel G. The wheel G is equipped with an annular friction member g'', which works in a groove in the side of the gear c, whereby the gear may be locked to rotate the shaft C through the medium of the wheel G. A spring g' tends normally to separate the gear and brake wheel, and a screw g'', equipped with a handle g'', serves to force the brake-wheel against the

gear. The brake-band g has one end joined by rods g' to the long arm of an automatically-acting brake-lock g'', comprising a rock member g'', journaled in bearings g'', and a spring g'', connected with the member g'' and with a stationary support. The brake-band has its other end joined by a rod g'' to the short arm of the member g''. As shown, the member g'' really has its arms divided into four parts, between the middle two of which is secured the rod g'' and between the two intermediates and the outer parts of which are secured the rods g'', the rod g'' passing between the rods g''. A pin g''' serves as a pivotal connection for the rods g'', and a pin g'''' serves as a pivotal connection for the rod g'', and it is to be observed that the pin g'''' is closer to the axis x of the member g'' than is the pin g'''. The spring g'' tends to hold the pin g''' depressed, and a stop g''', carried by the member g'' by engagement with the frame member g''', which supports the bearings g'', positively limits the rotation after the spring g'' has acquired a certain expansion.

The manner of use will be readily understood. Power may be communicated to the shaft B from a gasoline-engine—say located at any convenient point. After the operator starts the engine he turns to the mechanism shown, and after first making sure that the brake-band e'' is loose he turns the handle g'' and couples the gear c to the brake-wheel G and so to the shaft C. The clutch mechanism F may be operated to connect the drum to the shaft D either before or after the shaft is set in motion. In the winding operation of the drum the brake-wheel G rotates in the direction shown by the arrow in Fig. 2, the frictional force upon the brake-band g thus operating against the tension of the spring g''. In case of such a mishap as would allow the drum to pay out the cable under the weight of a car located on an inclined track the wheel G would reverse its movement, thereby causing the friction upon the band g to act with the spring g'' and cause the strap to grip the brake-wheel G, which would thereby effectually hold against retrograde movement. Inasmuch as the pinion c' acts on the large gear d, it is obvious that the drum-shaft is held with multiplied force. It is understood, of course, that when it is desired to lower a car the drum may be disconnected from its clutch and controlled manually by its direct brake through the hand-wheel on the screw e''.

What I regard as new, and desire to secure by Letters Patent, is—

1. The combination with a drum-shaft, a drum journaled thereon, a clutch for the drum, and a manually-controlled brake for said drum, of a shaft geared to the drum-shaft, and an automatic brake for said second-named shaft which permits rotation in the winding operation and automatically 10 grips to prevent reverse rotation, for the purpose set forth.

2. The combination with a hoisting-drum, of a driving-shaft geared to the shaft of the drum and equipped with a loose gear through 15 which it may receive power, an adjacent shiftable brake-wheel keyed on the driving-shaft,

a friction-clutch between the gear and brake wheel, means for shifting the brake-wheel, a brake-strap, a pivoted locking member with which the respective ends of the brake-strap are connected at different distances from the pivot of the locking member, and yielding means acting in a direction opposed to the force exerted by the brake-strap upon the long arm of the locking member and serving, 20 when the direction of the brake-wheel is reversed, to effect locking of the brake-wheel, for the purpose set forth.

WALTER H. BALDWIN.
